(57) **CLAIM**

The ornamental design for a bicycle rack, as shown and described.

DESCRIPTION

1. Bicycle rack

1.1 : Perspective

1.2 : Front

1.3 : Back

1.4 : Left

1.5 : Right

1.6 : Top

1.7 : Perspective

The design is for a bicycle rack including hooked locking bars having an extended state in which the hooked bars extend out of a plane of the rack frame (figures 1.1 to 1.6) and a folded state in which the hooked bars lie within the plane of the rack frame (figure 1.7); a central portion of the frame is absent; front and back views are identical; left and right views are identical; a bottom view is omitted: the bottom is flat and devoid of surface ornamentation; figure 1.1: perspective (extended state); figure 1.2: front; figure 1.3: back; figure 1.4: left; figure 1.5: right; figure 1.6: top; figure 1.7: perspective (folded state).
